UNITED STATES PATENT OFFICE.

HENRY BOLZE, OF HAWTHORNE, NEW YORK, ASSIGNOR TO THE SICILIAN ASPHALT PAVING COMPANY, OF NEW YORK, N. Y., A CORPORATION OF NEW YORK.

WATERPROOF CONSTRUCTION.

SPECIFICATION forming part of Letters Patent No. 739,820, dated September 29, 1903.

Application filed March 14, 1903. Serial No. 147,717. (No model.)

To all whom it may concern:

Be it known that I, HENRY BOLZE, a citizen of the United States, and a resident of Hawthorne, in the county of Westchester and State 5 of New York, have invented certain new and useful Improvements in Waterproof Construction, of which the following is a specification.

My invention relates to waterproof construction applicable to buildings or walls, and particularly adapted for use in tunnels and other underground-work.

The object of my invention is to provide a simple and very efficient method of constructing walls that are absolutely waterproof.

The invention will be fully described hereinafter and the features of novelty pointed out in the appended claims.

Reference is to be had to the accompanying drawings, in which—

Figure 1 is a partial longitudinal sectional elevation illustrating the construction of a tunnel in accordance with my invention, the section being taken on line 1 1 of Fig. 2; and 25 Fig. 2 is a cross-section on line 2 2 of Fig. 1.

The outer structure or foundation may be made in any suitable manner. Thus I have shown a concrete bottom A and an outer wall B, which may be constructed of common brick.

30 The inner faces of the bottom A and of the outer wall B are lined with two or three layers of waterproofing paper C C' or equivalent material. Upon the bottom layer C, I spread a molten asphalt mixture D, preferably of a

35 composition disclosed in another application for patent filed by me concurrently herewith. Into this molten asphalt mixture I place bricks E, which have been previously heated, so as to avoid chilling the asphalt mixture. Ac-

40 cording to requirements one or more courses of such bricks are laid in the asphalt mixture. Two courses are shown in the drawings. The bottom having thus been constructed, I proceed as follows to build the waterproof

45 wall on the inside of the lining C': At a distance from the said lining C' which corresponds to the intended thickness of the wall I erect a temporary wall, which may be made of planks F, resting against uprights G, which

50 are held in position by floor-braces h and inclined braces J. At first only the bottom

plank is in position, and the molten asphalt mixture is placed on top of the upper course of bricks E between said plank and the lining C'. Then bricks E', heated, as before described, 55 are placed in the molten asphalt mixture. If the retaining-plank F were not provided, the asphalt mixture would be caused to run down on the inner surface of the wall and would, moreover, be expelled from between the bricks 60 E'; furthermore, there would be danger of the bricks E' slipping out of their position, as the asphalt mixture is still in a fluid or semifluid condition. As soon as the top of the bottom plank F is reached the second plank is added 65 at the top, and in this manner the wall is continued upward until the top is reached. In this manner I am enabled to produce a vertical wall, notwithstanding the employment of a molten asphalt mixture as a binder or mortar 70 for the bricks.

Owing to their heated condition, the bricks have no chilling influence upon the asphalt mixture and absorb some of this mixture into their pores, whereby the entire structure is 75 rendered absolutely waterproof. Furthermore, the joints between the bricks and courses are filled by the hardened asphalt mixture, and the finished structure therefore forms a continuous waterproof wall. 80

It will be understood that if curved walls are to be built in accordance with my invention the planks or other temporary support will be given the appropriate shape.

What I claim as new, and desire to secure 85 by Letters Patent, is—

1. The herein-described improvement in waterproof construction, which consists in placing a molten asphalt mixture upon a suitable foundation, laying heated bricks in said 90 molten mixture and applying a retaining-body against the exposed surface of the structure so as to hold the latter steady until the asphalt mixture shall have become hard, and to prevent the molten mixture from being 95 expelled from between the bricks and from overflowing onto the exposed surface of the structure.

2. The herein-described improvement in waterproof construction, which consists in 100 preparing a suitable foundation or outer structure, applying a lining of waterproof mate-

rial on the inner surface of said structure, placing a molten asphalt mixture upon the upper surface of said lining, laying heated bricks in said mixture, placing an upright 5 retaining-body at a distance from the upright portion of said waterproof lining, erecting a wall of heated bricks laid in molten asphalt mixture between the upright portion of the lining and said retaining-body, and raising

said retaining-body as the erection of the 10 wall proceeds.

In testimony whereof I have hereunto set my hand in the presence of two subscribing witnesses.

HENRY BOLZE.
